US0D1021784S

(12) **United States Design Patent** (10) Patent No.: **US D1,021,784 S**
(45) Date of Patent: ** Apr. 9, 2024

(54) **CHARGING UNIT**

(71) Applicant: **Vorwerk & Co. Interholding GmbH**,
Wuppertal (DE)

(72) Inventors: **Thomas Lessel**, Velbert (DE); **Jan
Delfs**, Bonn (DE)

(73) Assignee: **Vorwerk & Co. Interholding GmbH**,
Wuppertal (DE)

(**) Term: **15 Years**

(21) Appl. No.: **29/814,138**

(22) Filed: **Nov. 3, 2021**

(30) **Foreign Application Priority Data**

May 5, 2021 (EM) 008529523-0001
May 5, 2021 (EM) 008529523-0002

(57)

CLAIM

The ornamental design for a charging unit, as shown and described.

DESCRIPTION

FIG. 1 is a top, right perspective view of the charging unit showing our new design;

FIG. 2 is a front view thereof;

FIG. 3 is a left side view thereof;

FIG. 4 is a back view thereof;

FIG. 5 is a right side view thereof;

FIG. 6 is a top view thereof; and,

FIG. 7 is a bottom view thereof.

The broken lines in the drawings depict portions of the charging unit that form no part of the claimed design.

1 Claim, 4 Drawing Sheets
